UNITED STATES PATENT OFFICE.

GEORGE I. KING, OF MIDDLETOWN, PENNSYLVANIA, ASSIGNOR TO AMERICAN CAR & FOUNDRY COMPANY, OF ST. LOUIS, MISSOURI, A CORPORATION OF NEW JERSEY.

GONDOLA CAR.

SPECIFICATION forming part of Letters Patent No. 766,701, dated August 2, 1904.

Application filed January 2, 1902. Serial No. 88,163. (No model.)

To all whom it may concern:

Be it known that I, GEORGE I. KING, a citizen of the United States, residing at Middletown, Pennsylvania, have invented a certain 5 new and useful Improvement in Gondola Cars, of which the following is a full, clear, and exact description, such as will enable others skilled in the art to which it appertains to make and use the same, reference being had to the accompanying drawings, forming part of this specification, in which—

Figure 1 is a side elevational view of my improved car, one end thereof being shown in vertical section. Fig. 2 is a top plan view of the car, the floor-sheets being removed at one end to more clearly show the underframing. Fig. 3 is an end elevational view, one side of the car being shown in section, the line of section being at the center of the car. Fig. 4 is 20 a sectional view of the car, taken in proximity to the body-bolster; and Figs. 5 and 6 are modified forms of the manner of supporting the inner edge of the platform-plate.

This invention relates to a new and useful 25 improvement in gondola cars of that type wherein hoppers are provided in the floor for discharging the greater portion of the load through the exit-openings. These exit-openings are closed by appropriate doors manipulated by suitable mechanism, and as these doors and the operating mechanism therefor form no part of my present invention I will not describe the same here in detail.

This present invention relates to a type of 35 car such as is shown in a companion application filed by me of even date herewith, in which companion application the side sheets, acting as plate-girders, are utilized for carrying the greater portion of the load. These 40 side sheets are made deepest at their middle portion, the tension-flanges thereof being provided by the floor-sheets in part, the inclined hopper-sheets in part, and reinforcing-angles in part, the latter being located in this 45 instance throughout the lower edges of the side sheets. These side walls in the form of plate-girders also support cross-beams located well

toward the center of the car, (said cross-beams being preferably located within the central cross-ridge,) which cross-beams support the 50 center sills.

The present invention consists in the construction, arrangement, and combination of the several parts, all as will hereinafter be described, and afterward pointed out in the 55 claims.

In the drawings, 1 indicates the end sills, 2 the center sills, which are preferably continuous from end sill to end sill, and 3 the body-bolsters.

4 indicates the side walls, which are made deepest at their middle portions, as shown in Fig. 1, and to which the downturned flanges of floor-sheets at the ends of the car are riveted, the line of attaching-rivets being located 65 above the lower edge of the shallow ends of the side walls.

6 indicates an angle whose vertical leg is arranged inside the lower edge of each side wall and whose horizontal leg projects outwardly beyond the lower edge of said side wall, said angle being bent appropriately to follow the lines of the lower edge of the side wall to which it is attached. This angle is 70 preferably continuous from end to end of the 75 car, and therefore it serves as a light side sill, it being placed in tension when the floor-loads are transmitted to the side wall.

7 indicates the ridge-sheet arranged in the center of the car, which sheet is flanged upwardly at its ends and attached to the side walls for the purpose of tying said side walls together.

8 indicates the cross-beams located within the cross-ridge and carried by the side walls 85 for supporting the center sills.

The hopper-sheets, inclined floor-plates, and floor-supports, in the form of angles, are arranged substantially as shown and described in my companion application, and as the same 90 are not claimed in this case they will not be described in detail.

In order to tie the lower edges of the side sheets at the center of the car, I arrange an

angle or angles 9 at this point and attach the same to the lower edge of the side wall by suitable rivets.

- By referring to Fig. 1 it will be noticed 5 that the end sill projects upwardly above the draft-sills and that the end wall of the car is located some distance back of the end sill. This enables the use of a platform-plate 10, which is preferably riveted to the top flange 10 of the end sill, and in order to support said platform-plate I may arrange vertical angles 11 thereunder, as shown in Fig. 2, but I prefer to employ the construction shown in Fig. 5 or Fig. 6, in the former of which a horizontal 5 angle 12 is riveted to the end wall and supports the inner edge of the platform-plate continuously throughout the width of the car, while in the latter form the inner edge of the platform-plate is flanged down, as shown at 10 13, and riveted to the end wall of the car, the same rivets being preferably employed in both forms that are used in attaching the end floor-sheet in position. In the construction shown in Fig. 5 it is obvious that angle 12 15 can be attached in position at the time the end floor-sheet is riveted in place, the platform-plate being subsequently riveted to the top flange of the end sill, its inner end being free and supported upon the angle 12. In the construction shown in Fig. 6 the platform-plate 20 is likewise riveted in position at the time the floor-sheet is attached in position and afterward the outer edge of the platform-sheet is riveted to the top flange of the end sill.
- 35 It will be noted that it is possible to use a machine-riveter for the purpose of driving most of the rivets employed in my construction, and consequently the cost of manufacture is greatly reduced.
- 40 I am aware that many minor changes in the construction, arrangement, and combination of the several parts of my device may be made and substituted for those herein shown and described without in the least departing 45 from the nature and principle of my invention.

Having thus described my invention, what I claim, and desire to secure by Letters Patent of the United States, is—

1. In a car, the combination with side walls, 50 made deepest at their middle portions, of angles, continuous from end to end of the car, and attached to the lower edges of said side walls, flanged floor-sheets riveted to the side walls above the angles at the ends of the car, center sills, and cross-beams carried by the side walls for supporting the center sills; substantially as described.

2. In a car, the combination with side walls, 55 made deepest at their middle portions, of angles, continuous from end to end of the car, and attached to the lower edges of said side walls, flanged floor-sheets riveted to the side walls above the angles at the ends of the car, center sills, cross-beams carried by the side 60 walls for supporting the center sills, and a

cross-ridge in the center of the car above the cross-beams, the top ridge-sheet of said cross-ridge being flanged upwardly and attached to the side walls of the car; substantially as described.

70

3. In a car, the combination with the side walls made deepest at their middle portions, of center sills, cross-beams carried by the side walls for supporting the center sills, and an angle arranged between the cross-beams and 75 attached to the lower edges of the side walls at the center of the car, for tying said side walls at this point; substantially as described.

4. In a car, the combination with the side walls, of a center sill, cross-beams carried by 80 the side walls for supporting the center sill, a cross-ridge carrying said cross-beams, the top ridge-plate thereof being flanged up at its ends and attached to the side walls of the car, and an angle 9 attached to the lower edges of 85 the side walls, at a point between the cross-beams for tying the lower edges of said side walls together at the center of the car; substantially as described.

5. In a car, the combination with an upwardly-projecting end sill, of a platform-plate 90 attached at its outer edge to the upward-projecting portion of said end sill, and means for supporting the inner edge of said platform-plate; substantially as described.

6. In a car, the combination with the end sill, of a platform-plate riveted to the top thereof and supported thereby at its outer edge, the end wall of the car, and means being attached to the end wall of the car for 100 supporting the inner edge of the platform-plate, substantially as described.

7. In a car, the combination with the end sill, of a platform-plate riveted to the top 105 thereof and supported at its outer edge thereby, the end wall of the car, and a flange attached to said end wall for supporting the inner edge of the platform-plate; substantially as described.

8. In a car, the combination with the end sill, of a platform-plate riveted to the top flange thereof, the end wall of the car, and means riveted to said end wall for supporting the inner edge of the platform-plate, the rivets forming an attachment of said means to the 115 end wall, also securing the end sheet in position; substantially as described.

9. In a car, the combination with a channel-shaped end sill, a separate platform-plate secured thereto and extending substantially 120 the length of said sill, said plate being secured to said sill at its outer edge and to the end wall of the car, and means for supporting the inner edge of said platform-plate; substantially as described.

10. In a car, the combination with a channel-shaped end sill, a separate platform-plate secured thereto, extending substantially the length of said sill, and of substantially uniform width from end to end and riveted to a 130

- flange of said sill at the outer edge of said plate, the end wall of the car, and means for supporting the inner edge of said platform-plate; substantially as described.
- 5 11. In a car, the combination with a channel end sill, of a platform-plate secured to the upper flange thereof, said plate extending substantially the length of said sill and being supported thereby at its outer edge, the end 10 wall of the car, and means connected with the end wall of said car for supporting the inner edge of said platform-plate; substantially as described.
12. In a car, the combination with a straight 15 channel end sill, of a separate platform-plate secured above the same by riveting to the upper flange thereof and extending substantially the length of said sill, said plate being of substantially the same width from end to end, 20 the end wall of the car, and means connected with the end wall of the car for supporting the inner edge of said platform-plate; substantially as described.
13. In a car, the combination of bolsters, 25 plate-girder sides supported by said bolsters and having compression and tension flanges which are parallel for a portion of their length, said plate-girder sides being deepest at their middle portion, and transverse transoms connected at their ends to the deeper portion of 30 said plate-girder sides; substantially as described.
14. In a car, the combination of center sills, 35 end sills extending to a higher plane than said center sills, plate-girder side walls deepest at their middle portion, a floor above said center sills connected with said side walls, tension-flanges connected with said side walls below said floor, and compression-flanges at the upper side of said side walls; substantially as described.
15. In a car, the combination of center sills, 45 end sills extending to a higher plane than said center sills, plate-girder side walls deepest at their middle portion, a floor above said center sills in a plane below the upper plane of said end sills, said floor being connected with said side walls, tension-flanges connected with said side walls below said floor, and compression-flanges at the upper side of said side walls; substantially as described.
16. In a car, the combination of center sills, 55 end sills, plate-girder side walls deepest at their middle portion, compression-flanges and tension-flanges connected with said side walls, and a floor above said tension-flanges and center sills, said floor resting in a plane below the upper plane of said end sills; substantially as described.
- 60 17. In a car, the combination of bolsters, plate-girder sides, a compression-flange, a flooring, a tension-flange below said flooring, and a cross-beam connected with downwardly-extended portions of said plate-girder sides, 65 between said bolsters; substantially as described.
18. In a car, the combination with a body-bolster, of plate-girder sides having lower or tension flanges, a floor connected with said plate-girder sides, an end sill extending to a plane above said floor, end walls, and a platform-plate connected with said end sill and said end wall above the plane of said floor; substantially as described.
19. In a car, the combination of plate-girder 75 sides, bolsters formed of flanged beams secured at their opposite ends to said girder sides, center sills which extend from end to end of the car and pass through said bolsters between the web portions thereof, and plates connecting said center sills and bolsters; substantially as described.
20. In a car, the combination of plate-girder 80 sides, bolsters formed of flanged beams secured at their opposite ends to said girder sides, center sills which extend from end to end of the car and pass through said bolsters between the web portions thereof, and plates above and below said bolsters connecting said center sills and bolsters; substantially as described.
21. In a car, the combination of plate-girder 85 sides, bolsters formed of flanged members secured at their opposite ends to said girder sides, center sills which extend from end to end of the car and pass through said bolsters, a cover-plate connecting said center sills and bolsters, a floor, an end sill which extends to a plane above said floor, and a platform-plate 90 in a plane above said floor connected with said end sill; substantially as described.
22. In a car, the combination of plate-girder 95 sides, bolsters formed of flanged members secured at their opposite ends to said girder sides, center sills which extend from end to end of the car and pass through said bolsters, a cover-plate connecting said center sills and bolsters, a floor above said center sills, an end 100 sill which extends to a plane above said floor, and a platform-plate in a plane above said floor connected with said end sill; substantially as described.
23. In a car, the combination of plate-girder 105 sides, of bolsters formed of channel-beams, an upper plate connected therewith, a lower plate connected therewith, said plates being riveted to the flanges of said channels and extending unbroken from end to end, center sills extending from end to end of the car between the webs of said bolsters and between 110 said plates, and connected with said plates; substantially as described.
24. In a car, the combination of plate-girder 115 sides, of bolsters formed of flanged beams, divided for center sills, center sills extending therethrough, top and bottom cover-plates 120 connecting said sills and flanged beams, end sills extending to a plane above said center 125

sills, and a floor in a plane below the upper plane of said end sills; substantially as described.

25. In a car, center sills composed of flanged members, a cover-plate connected with the flanges thereof, extending longitudinally of said sills, an end sill extending to a plane above said center sills, a floor below the upper plane of said end sill, and plate-girder side walls, with tension-flanges extending longitudinally thereof below the plane of said floor; substantially as described.

26. In a car, the combination of plate-girder sides, center sills extending from end to end of the car, bolsters formed of flanged beams secured at their opposite ends to said girder sides, said bolsters having divided webs between which said center sills pass, and plates riveted to the upper flanges of the bolsters and extending across said center sills; substantially as described.

27. In a car, the combination of plate-girder sides, center sills composed of flanged members extending from end sill to end sill, a longitudinal plate connected with the flanges of said center sills, and end sills composed of channel members extending to a plane above said center sills; substantially as described.

28. In a car, the combination of plate-girder sides, center sills composed of flanged members extending from end sill to end sill, a longitudinal plate connected with the flanges of said center sills, end sills composed of channel members extending to a plane above said center sills, and a platform-plate connected respectively to said end sill and an end wall of the car; substantially as described.

29. In a car, the combination of plate-girder sides, center sills composed of flanged members extending from end sill to end sill, a longitudinal plate connected with the flanges of said center sills, end sills composed of channel members extending to a plane above said center sills, and a cross-beam between the bolsters connected at its ends with said plate-girder sides; substantially as described.

30. In a car, the combination of plate-girder sides, center sills composed of flanged members extending from end sill to end sill, a longitudinal plate connected with the flanges of said center sills, end sills composed of channel

members extending to a plane above said center sills, bolsters comprising flanged web portions divided for the center sills, and a cover-plate connected respectively with said flanged portions and with the center sills; substantially as described.

31. The combination of body-bolsters, a center sill or sills, girder sides having tension-flanges on their outer sides which are supported by the bolsters and are depressed between the bolsters below the tops of the latter, and hoppers arranged between and secured to said girder sides and the center sill or sills and having bottoms which incline upwardly toward the center of the car; substantially as set forth.

32. The combination of body-bolsters, a center sill or sills, girder sides which are supported by the bolsters and extend down between the bolsters below the tops of the latter, and hoppers arranged between and secured to said girder sides and the center sill or sills and having bottoms which incline upwardly toward the center of the car, substantially as set forth.

33. The combination of body-bolsters, a center sill or sills, girder sides which are supported by the bolsters and extend down between the bolsters below the tops of the latter, and hoppers arranged between and secured to said girder sides and the center sill or sills and having bottoms which incline upwardly toward the center of the car, and a horizontal floor extending from said hoppers to the end of the car, substantially as set forth.

34. The combination of body-bolsters, a center sill or sills, girder sides which are supported by the bolsters and extend down between the bolsters below the tops of the latter, hoppers between said girder sides and the center sill or sills and having bottoms which incline upwardly toward the center of the car, and a horizontal floor between said hoppers and between the hoppers and the ends of the car, substantially as set forth.

In testimony whereof I hereunto affix my signature, in the presence of two witnesses, this 20th day of December, 1901.

GEORGE I. KING.
